UNITED STATES PATENT OFFICE.

JOHN N. GORMAN, OF RICHMOND, VIRGINIA.

TRUNK-STRAP.

No. 891,835.

Specification of Letters Patent. Patented June 30, 1908.

Application filed July 26, 1907. Serial No. 385,694.

To all whom it may concern:

Be it known that I, JOHN N. GORMAN, a citizen of the United States of America, and resident of Richmond, county of Henrico, State of Virginia; have invented certain new and useful Improvements in Trunk-Straps, of which the following is a full and clear specification, reference being had to the accompanying drawing, in which—

10 Figure 1 is a perspective view of the buckle showing it closed; Fig. 2 a perspective view showing the buckle opened and the two members separated, in position to be connected and swung over to closed locking position; 15 Fig. 3 a vertical longitudinal sectional view showing the buckle closed; and Fig. 4 a perspective view of the locking or keeper member of the buckle.

This invention has reference to that class 20 of trunk and other straps in which a suitable lock is carried by a lever-like member to which the adjustable end of the strap is connected and which is pivotally connected to a main member or keeper, and the object of the 25 present invention is to simplify and improve the construction of this type of devices, as more fully hereinafter set forth.

Referring to the drawings annexed by reference characters, A designates the keeper member which at its forward end is provided with a transverse keeper bar *a* which is elevated above the upper surface of the main plate of the member. Near the forward end this plate A is provided with a transverse 35 slot *b* and near its rear end is provided with a pair of adjacent transverse slots *c*, *c*, and at its extreme rear end this plate is provided with an upturned hook *d* which opens forwardly. One end of the strap is fastened to 40 this member by passing it down through slot *b* and along the under side of the member and threading it through the slots *c*, *c*, the end of the strap terminating at a point beyond the rearmost slot *c*.

45 The lever member B is provided with a suitable key lock *e* which is suitably fastened to its under side between the side flanges of the member, with its locking bolt *f* pointing forward and in such position that when the lever member is forced down upon the main member the said locking bolt will snap under the keeper bar *a* and thus hold the parts in locked relation until said bolt is withdrawn by means of a suitable key. At the rear end this lever member is provided with a transverse pivot bar *g* which fits and works in the

open hook *d*. This lever member is connected to the free end of the strap by having the end of the strap passed down through a transverse slot *h* and up through a similar transverse slot *h'*, the free extremity of the strap passing backwardly over the pivot bar *g*. 60

To adjust the strap to a trunk after the strap has been passed around the trunk in the usual manner, the lever member being detached from the keeper member, it is simply necessary to pull the free end of the strap through the slots *h*, *h'*, to a point that will enable the operator to just hook the 70 pintle *g* over the hook *d*, the lever member lying lock-side up as shown in Fig. 2. Then by swinging the lock-carrying member over in the manner of a lever and forcing it down upon the main member until its locking bolt 75 engages the keeper of the main member, the strap will be drawn taut around the trunk and locked.

It will be observed that by my manner of attaching the buckle to the straps the 80 metal parts of the buckle will be supported up off the trunk by means of the peculiar manner of threading the keeper member on the end of the strap. It will be observed also that by making the lever member separable from the other member so that it 85 may be lifted up off the trunk and freely handled while the free end of the strap is being adjusted, the operator may adjust the strap to the proper point in the buckle with but a single adjustment. It will be observed also that by reason of the rigid connection 90 between that part of the main member which forms the keeper and that part which forms the fulcrum of the lever member the distance 95 between the axis of the pivot and fulcrum and the keeper bar will always remain the same so that the locking bolt will always strike the keeper plate and engage the same, even after long continued use of the device, 100 whereas if the fulcrum of the lever member be connected to the keeper-carrying part of the member by a flexible connection, continued use of the device would stretch the 105 flexible connection and throw the keeper out of alinement with the lock bolt.

Having thus fully described my invention, what I claim as new and desire to secure by Letters Patent, is—

In a device of the class set forth, the combination of a main member provided with a keeper at its forward end and a fulcrum at

its rear end and also with three transverse slots, one at its forward end in front of the keeper and the other two near its rear end adjacent to the fulcrum, a trunk strap having one end threaded down through the forward slot and up and down through the other slots and extended beyond the end of the member, whereby the threaded end of the trunk strap will prevent the member 10 from having contact with the trunk, and a lock-carrying member attached to the other

end of the strap and provided with a pivot engaging the fulcrum at the rear end of the main member.

In testimony whereof I hereunto affix my 15 signature in the presence of two witnesses this 22nd day of July, 1907.

J. N. GORMAN.
